(57) **CLAIM**

The ornamental design for a media player dock clock radio, as shown and described.

DESCRIPTION

FIG. 1 is a top, front, perspective view of a media player dock clock radio showing my new design;

FIG. 2 is a front view thereof;

FIG. 3 is a rear view thereof;

FIG. 4 is a top view thereof;

FIG. 5 is a bottom view thereof;

FIG. 6 is a side view thereof, the opposite side view being a mirror image; and,

FIG. 7 is an oblique view in the direction of arrow 7 in FIG. 4.

The broken lines in the drawings illustrate environmental material that forms no part of the claimed design.
